ATTORNEY

UNITED STATES PATENT OFFICE.

EDWARD FLANAGAN, OF PHILADELPHIA, PENNSYLVANIA.

SMOKE-HOUSE.

1,271,300.

Specification of Letters Patent.

Patented July 2, 1918.

Application filed April 20, 1917. Serial No. 163,452.

To all whom it may concern:

Be it known that I, EDWARD FLANAGAN, a citizen of the United States, residing at 1430 Blavis street, Philadelphia, in the 5 county of Philadelphia and State of Pennsylvania, have invented new and useful Improvements in Smoke-Houses, of which the following is a specification.

This invention relates to smoke houses, 10 and has for an object, among others, to provide a novel and improved form of smoke generating apparatus, which embraces automatic features of control and operation, tending to produce a more efficient and more 15 economically operating means for maintaining the temperature of the smoke house within prescribed limits.

Another object resides in the provision 20 of the smoke house which economizes fuel when in operation and serves to insure a positive circulation of smoke throughout every part thereof, without resorting to the use of circulating fans and similar appurtenances.

25 A further object resides in a smoke house having a smoke generating apparatus positioned therein, and an oscillating damper for controlling the circulation of smoke through the closure, a chain being connected 30 with said damper to retain the same in an open position and with the smoke outlet door or damper of said apparatus, a fusible link is provided in the chain so that when the temperature within the smoke house 35 reaches a predetermined limit, said link will fuse so as to destroy the chain connection existing between the dampers, in order that the latter may revolve to closed positions, whereby the temperature of the 40 building will be instantly lowered.

The invention consists of novel features, details of construction and combination of parts, which hereinafter will be more particularly set forth, illustrated and claimed.

45 In the drawing—

Figure 1 is a vertical section of a smoke house, and appliances embodying the preferred form of the invention.

50 Fig. 2 is an enlarged vertical sectional view of the smoke generating apparatus or furnace, and

Fig. 3 is a detail view of the smoke house damper, illustrating the application of the fusible link to the chain thereto.

Similar characters of reference denote 55 corresponding parts throughout the several views of the drawing.

Referring more particularly to the drawing, the preferred form of the invention consists of a smoke generator 1, which is 60 positioned interiorly of a smoke house 2, the latter may be of any appropriate size, or constructed from any suitable material, and is preferably heated through the agency of steam-heated coils 3 or their equivalent, 65 whereby the temperature of the house may be maintained at a required degree necessary to properly conserve edible materials positioned therein.

The generator 1 in its preferred embodiment consists of a sheet metal structure which is internally divided, by means of a wall or partition 4, to define a fuel-receiving hopper 5 and a combustion chamber 6. Access is to be had to the hopper through 70 the agency of a hinged cover 7, whereby suitable fuel, such as saw dust obtained from certain woods, may be readily positioned therein. The lower wall of the hopper 5 is preferably inclined toward the 75 lower portion of the combustion chamber 6, so that fuel positioned within the hopper will automatically gravitate toward said combustion chamber as it is consumed or needed.

Air is supplied to the chamber 6 through the use of a substantially funnel-shaped pipe 8, which communicates with the exterior of the smoke house and terminates interiorly within the combustion chamber in 80 a downwardly extending nozzle 9. Said pipe is adapted to supply a sufficient quantity of fresh air to the generator to conform 85 with the combustion requirements of the latter, and practice has proven the fact that 90 by virtue of this construction it is not necessary to employ a fan or blower, such as used in the construction covered by my former Patent #1,133,118. Smoke escapes 95 from the combustion chamber through a 100 damper-covered outlet 10 provided in the upper extremity of the chamber 6, and is then adapted to circulate through the smoke house so as to be utilized in curing suitable foods. A cupola 11 is provided on 105 the upper portion of the smoke house, and is formed with a smoke outlet opening 12, and by reason of this construction it will be

seen that air will be permitted to circulate through the smoke house in a constant and steady stream, when the damper 13, is in an open position.

- 5 The smoke outlet 10 of the generator 1 is adapted to be covered by means of a door or damper 14 which, when the generator is in service, is in an open position, clearly indicated in Fig. 1, so that smoke produced 10 within the chamber 6 will be free to escape from the generator and circulate through the confines of the smoke house. The dampers 13 and 14 are normally retained in an open position through the use of a chain 15, or an 15 equivalent, the latter having the extremities thereof suitably secured to the dampers, so as to hold the latter in the open positions indicated by the drawings, pulleys 16 being utilized to control the movements of the 20 chain. A fusible link 17 is employed to connect the chain 15 with the damper 13 and it will be seen that in the event of the temperature of the smoke house reaching an abnormal or dangerous point the link 17 will 25 fuse so that the connection existing between said damper 13 and the chain will be broken. This action will permit the damper 13 to revolve to a closed position, shutting off the circulation through the smoke house, and at 30 the same time will release the damper 14 so as to cover the combustion chamber 6. By this construction it will be possible to economically cure food stuffs positioned within the smoke house, as the proper temperature 35 required for properly curing such matter is always maintained, and excessive waste-producing temperatures are accordingly eliminated. When the damper 14 revolves to a 40 closed position, the supply of fuel from the hopper 5 to the combustion chamber is also automatically cut off, as said damper is connected by means of a link 18 with a pivoted door 19, associated with the wall 4 and designed to control the passage of the fuel into 45 said combustion chamber, as will be clearly understood. The link 18 also serves to open the door 19 when the damper 14 is elevated to permit of the rise of smoke within the closure 2.
- 50 From the foregoing description it is thought that the operation and construction of the present invention will be clearly obvious to those versed in the art, and there-

fore a more extended explanation relative thereto, will be accordingly omitted.

55

I claim:

1. In a smoke house, the combination with a smoke generator having a combustion chamber formed therein, of an air supplying means extending from said chamber to the exterior of said smoke house, and a pivoted damper covering the smoke outlet of said chamber.

60

2. In a smoke house, the combination with a smoke generator having a combustion chamber formed therein, of an air supplying means extending from said chamber to the exterior of said smoke house, and a pivoted gravity closing damper covering the smoke outlet of said chamber.

65

3. A smoke house having a smoke generator positioned therein, an air inlet extending from the exterior of said smoke house to the combustion chamber of said generator, gravity closing dampers covering the smoke outlets of said smoke house and generator when the internal temperature of said smoke house reaches a predetermined height.

70

4. In a smoke house, the combination with a smoke generator including a combustion chamber, of an air-supplying means extending to said chamber from the exterior of said smoke house, a fuel-receiving hopper provided in said generator, a swinging door controlling the flow of fuel from said hopper to the combustion chamber, a similar door for regulating the smoke outlet of said combustion chamber, and means connecting said doors whereby the latter will move in unison.

75

5. In a smoke house, the combination with a smoke generator, an air inlet pipe extending from the exterior of said smoke house to said combustion chamber, a damper controlling the smoke outlet of said combustion chamber, a similar damper for controlling the circulation of smoke through said smoke house, a chain connecting said dampers to normally retain the latter in open positions, and fusible means carried by said chain to destroy the connection existing between said dampers when the temperature within said smoke house reaches a predetermined height.

80

In testimony whereof I affix my signature. 105
EDWARD FLANAGAN.
